UNITED STATES PATENT OFFICE.

OSCAR L. MEEKS, OF ABILENE, KANSAS, ASSIGNOR OF ONE-HALF TO JOHN J. MEEKS,
OF KANSAS CITY, MISSOURI.

COOLER.

1,024,014.

Specification of Letters Patent. Patented Apr. 23, 1912.

Application filed April 21, 1911. Serial No. 622,620.

To all whom it may concern:

Be it known that I, OSCAR L. MEEKS, a citizen of the United States, residing at Abilene, in the county of Dickinson and State of Kansas, have invented certain new and useful Improvements in Coolers; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to coolers and more particularly to a device for household use in localities where ice cannot be procured; the object of my invention being to provide means for producing a film of water in 20 front of suitable supports, upon which the articles to be cooled are placed, so that air passing through the film of water will be cooled and thereby cool the articles on the support. In accomplishing this object, I 25 have provided the improved details of structure hereinafter described and illustrated in the accompanying drawings, wherein:—

Figure I is a perspective view of a cooler constructed according to my invention, part 30 of the curtain covering being broken away. Fig. II is a longitudinal vertical section through the upper part of the cooler and tank. Fig. III is a transverse vertical section of same, showing the tank in end elevation.

Referring more in detail to the parts:— 1 designates a stand having corner posts 2 which support shelves 3, and in turn are preferably supported in a suitable basin or 40 receptacle 4. On the top of the stand 1, is a pan 5 having flaring sides 6, over which is hung a curtain 7, which is preferably of loose woven fabric so that it will absorb water and permit the passage of air there- 45 through. The upper end of the curtain preferably extends entirely around the pan and is hung therein so that it may touch the bottom thereof, the lower end being suspended within the basin 4. Supported 50 within the pan 5 is a tank 8 of any suitable size and construction, but preferably cylindrical and supported on legs 9. Within one end of tank 8, near the lower edge thereof,

so that it will come below the water line in the pan, is an aperture 10, and opening 55 through the end of the tank at about the same level as the aperture 10, is a tube 11 which extends to and opens into the upper portion of the tank. Extending through the top of the tank is a tube 12, having a funnel 60 13 at the top and having an open end 14 adapted for discharging at the bottom of the tank.

In using the device, the articles to be cooled are placed on the stand shelves and 65 the curtain hung in place, as partially illustrated in Fig. I. The tank is filled through the funnel 13, so that the water is discharged at the bottom of the tank and rises therein, forcing the air to the top and thence downwardly through the tube 11 to the outlet 70 below the water line of the pan. Water escaping through aperture 10 in the tank partially fills the pan and is taken up by the curtain fabric in the same manner as an ordinary wick, passing down through the material in front of the shelves, so that the liquid that does not evaporate during the descent, is caught in the basin.

With the device located in the open air, 80 air passing through the water soaked curtain becomes cooled and cools the articles supported on the shelves.

Having thus described my invention, what I claim as new therein and desire to secure 85 by Letters-Patent is:—

The combination with a stand, having shelves, of a pan mounted on said stand over the shelves, a curtain hung over the stand and having its upper end located within the pan, 90 a tank seated on the bottom of the pan, one end of the tank having an opening therein within the pan, and a tube having a passage of the same diameter as the opening, located within the tank, the lower end of the tube 95 being projected through the end of said tank level with the opening and the upper end of the tube opening into the upper part of said tank.

In testimony whereof I affix my signature 100 in presence of two witnesses.

OSCAR L. MEEKS.
